HORACE A. CARTWRIGHT, OF TOLEDO, OHIO, ASSIGNOR TO THE SURFACE COMBUSTION COMPANY, INC., OF TOLEDO, OHIO, A CORPORATION OF NEW YORK

CONVEYER FOR USE WITH FURNACES

Application filed May 18, 1928. Serial No. 278,682.

This invention relates generally to improvements in conveyers of the type adapted to progress or translate material step by step along a given path of travel.

5 The invention has among its objects to provide a conveyer of the type indicated which shall be particularly well adapted for use in connection with furnaces wherein the conveyed material is to be heated, which shall be 10 simple in construction, reliable in operation, and otherwise well adapted for its intended purpose.

In accordance with this invention the conveyer comprises in combination with a supporting means on which the material to be conveyed is normally supported between periods of translation or progression, a material progressing means which includes a reciprocable carriage and a material translating 20 member supported by and reciprocable with respect to said carriage.

For a more complete understanding of the invention reference is made to the detailed description and the accompanying drawings 25 forming part of this specification.

In the drawings, Fig. 1 is a side elevation of a bolt-blank heating furnace having the improved conveyer associated therewith;

Fig. 2 is a side elevation on an enlarged 30 scale of a portion of the conveyer mechanism shown in Fig. 1;

Fig. 3 is a cross section of the furnace and conveyer shown in Fig. 1;

Fig. 4 is a cross section of the conveyer, the 35 view being taken on line 4-4 of Fig. 2;

Fig. 5 is a cross section of a modified form of conveyer embodying the principles of the present invention;

Fig. 6 illustrates how the form of the invention shown in Fig. 5 is adapted for use 40 with a furnace through which the whole of an object may be passed for heating, and

Figs. 7 and 8 are schematic views for explaining the cycle of movement of the conveyer mechanism.

The conveyer mechanism comprises among its elements a reciprocable carriage, a stepped track on which the carriage travels, a work elevating and translating member mounted 50 for reciprocation on said carriage, and means

for supporting the work between periods of elevation and translation.

The conveyer mechanism illustrated in Figs. 1 to 4 is adapted for use in connection with a trunnel-like furnace having a longitudinally extending side opening 10 through which the work, as for example, bolt blanks 11 may project into the furnace chamber from the outside thereof. The furnace is shown as supported on a bench-like frame work 12 which at one side has an elevated portion 14 on which the conveyer mechanism is supported.

55 Suitably secured to said elevated portion 14 of the frame work 12 is a longitudinally extending channel iron 16 which constitutes the base of the conveyer. Secured to the sides of said iron at appropriate points along its length are oppositely positioned, relatively short, stepped track sections generally indicated by letter A. The track surface of each of said sections is the same and includes lower and upper runways 18 and 20, respectively, connected by an inclined runway 22. On these track sections, a carriage generally indicated by letter B is adapted to be reciprocated.

60 The carriage is a relatively long affair. The frame work of the carriage includes a pair of laterally spaced, longitudinally extending angle irons 24 which are cross connected at appropriate points by elements 26. These elements are preferably castings having a raised and cored boss 27 for supporting individual shafts 28. Mounted on the projecting ends of each shaft are carriage supporting rollers 30 adapted to run on the tracks A. The rollers are kept to their tracks by guide blocks 32 which extend between opposite track sections and which are secured to the side flanges of the angle irons 24. Also mounted on the ends of each shaft 28 are rollers 34 on which the work elevating and translating member generally indicated by letter C is mounted for reciprocation.

65 The work moving member C comprises a pair of laterally spaced, longitudinally extending rails 36 cross connected at suitable points by tie rods 38 (see Fig. 2). The inner bottom corners of the rails are angled as in

dicated at 40 to form runways for the outer rollers 34. The rails may be of hollow construction as shown to permit the passage of cooling water therethrough.

The means for supporting the work between periods of translation is indicated generally by letter D and comprises a pair of laterally spaced, longitudinally extending rails 42 cross connected at appropriate points by brackets 44 having a depending pillar or post 46 provided with a base 48 for securement in any suitable manner to the base channel iron 16.

As already indicated, the carriage B and work moving member C are adapted for relative reciprocation in a manner hereinafter explained. At this point it will be sufficient to say that the means for reciprocating said carriage and member may take the form of a crank shaft with appropriate connecting rods. A simple driving arrangement is shown in Fig. 1. An electric motor 50 is utilized to drive two cranks of different throw or radius positioned at right angles to each other. One of these cranks is indicated by reference character 52 and the other by 54. Extending from crank 54 to the work moving member C is a pitman 56 and from crank arm 52 to the carriage B is a pitman 58. These pitmen connect with the reciprocable means at suitable points as will be readily understood. Thus pitman 58 may connect with the carriage through lugs 60 (see Fig. 4) depending from the carriage element 26 and the pitman 56 to the adjacent end of the member C.

Before describing the mode of operation of the conveyer mechanism thus far described, the modified form of the invention shown in Figs. 5 and 6 will first be described. The modified form of the invention is primarily adapted for use with furnaces of the type indicated in Fig. 6, that is to say, with furnaces into which the work as a whole may be entered for passage therethrough. The furnace is shown as having a hearth or floor below which the major part of the conveyer mechanism is positioned. The furnace floor is divided longitudinally by channel and slot both generally indicated by reference character 62. Positioned in the channel is a work elevating and translating member C' consisting of a pair of laterally spaced, longitudinally extending rails 36' cross connected by brackets 64 at appropriate points. Each bracket is mounted on or forms the top of a pedestal or post 66 having a base 68 by means of which it is secured to a reciprocating member which, together with the rails 36' within the furnace chamber, constitutes the work elevating and translating means C' having the same mode of operation as the previously described member C.

The hearth sections D' on either side of the channel and slot 62 together serve to support

the work between periods of elevation and translation by the member C'. The member C' is a frame work which includes, in addition to the parts already mentioned, a pair of laterally spaced, longitudinally extending channel irons 70 which are secured to the tops of the pedestal bases 68 for the purpose of making up a rigid structure. The bases 68 are sufficiently broad lengthwise of the channel irons 70 to provide a runway for rollers 34' on which the member C' as a whole is supported. The rollers 34' are part of a carriage B' corresponding to the previously described carriage B. While the two carriages are shown as differing somewhat in details of construction, functionally they are the same. The frame of carriage B' is made up of a single longitudinally extending channel iron 72, the side flanges being turned downward. The carriage supporting rollers 30' are mounted in pairs, a pair for each track section A' which, as shown, is of twin construction but having the same type of stepped surface as the previously described track A. As a means for confining the rollers 30' to their tracks there is provided on each track section a ridge 74 on either side of which the rollers run.

The mode of operation of the conveyer will now be described. Between periods of translation the work is supported on the fixed support D (D'). As carriage B (B') moves back and forth on its track A (A'), the work moving member C (C'), which is supported on the carriage, is alternately raised and lowered with respect to the fixed support and consequently the work on the support will be alternately raised and lowered. The work being raised clear of the support by the member C (C'), the latter is moved horizontally to shift the work longitudinally of said support. Upon completion of its work shifting stroke, the member C (C') is lowered to redeposit the work on the support, the lowering of said member taking place by reason of the carriage travelling down the incline 22 of its track A (A'). Upon the carriage arriving at the lower level 18 of its track, the member C (C') begins to move back toward its starting point and continues so to move while the carriage moves forward and backward on its lower track level 18. Upon the carriage reaching the incline 22 on its return stroke, the forward movement of the member C (C') will be coming to an end. By the time the carriage reaches the top of the incline 22, the member C (C') is ready for its work shifting stroke. During the work shifting stroke of member C (C') the carriage moves forward and backward on the upper track surface 20.

The cycle of movement above described may be more readily understood by reference to Figs. 7 and 8. The large circle 52^a in Fig. 7 indicates the orbit of the carriage crank 52 and the large circle 54^a the orbit of the

crank 54 for the work moving member C, these circles being divided into twelve equal parts to facilitate description. Crank 54 is 90° in advance of crank 52. When the crank 52 is at c' the carriage B is moving toward the left on its upper track level 20. The corresponding position of crank 54 is at w' . The work moving member C is therefore moving toward the right. When crank 52 is at c^2 , crank 54 is at w^2 . Member C is therefore approaching the end of a stroke whereas carriage B is about to move down the inclined track surface 22 whereupon member C will be lowered to redeposit the work on the fixed supports. When crank 52 is at c^3 , crank 54 is at w^3 from which it will be seen that member C is moving in opposition to the carriage B. When crank 52 is at c^4 , crank 54 is at w^4 . The carriage B is therefore about to move up the inclined track surface 22 and member C is approaching the end of its stroke. From the foregoing description the mode of operation of the conveyer should be readily apparent.

25 A conveyer constructed in accordance with the present invention is relatively simple in construction and is readily adaptable to different types of furnaces as indicated in Figs. 3 and 6. As indicated in Fig. 1 the work 30 will preferably be delivered to the conveyer from a source of supply such as a hopper.

What is claimed is:

1. In a conveyer adapted to move objects step by step along a work support, the combination of means forming said support, a reciprocable carriage movable in one plane for a portion of its length of travel and in a higher plane for the remainder of said length, and independently reciprocable means mounted 40 on said carriage for moving the objects along said support when the carriage is moving in said higher plane.

2. In a conveyer adapted to move objects step by step along a work support, the combination of means forming said support, a reciprocable carriage below said support, means for causing said carriage to travel in one plane for a portion of its length of travel and in a higher plane for the remainder of 50 said length, and independently reciprocable means mounted on said carriage for moving the objects along said path when the carriage is moving in said higher plane.

3. In a conveyer adapted to move objects 55 step by step along a work support, the combination of means forming said support, a reciprocable carriage below said support, a track on which said carriage is supported for travel, said track for a portion of its 60 length being in one plane and in a higher plane for the remainder of said length whereby the carriage in traversing the length of said track moves in two successive planes, and independently reciprocable means 65 mounted on said carriage for moving the

object along said support when the carriage is moving in said higher plane.

4. A conveyer according to claim 1 characterized by the fact that said carriage has a longer length of travel than said independently reciprocable means. 70

5. A conveyer according to claim 2 characterized by the fact that said carriage has a longer length of travel than said independently reciprocable means.

6. A conveyer according to claim 3 characterized by the fact that said carriage has a longer length of travel than said independently reciprocable means. 75

7. A conveyer as claimed in claim 1, including means for reciprocating said carriage and said independently reciprocable means in a manner to cause the carriage to reverse its direction of travel after said reciprocable means has reversed its direction of travel. 80

8. A conveyer as claimed in claim 2, including means for reciprocating said carriage and said independently reciprocable means in a manner to cause the carriage to reverse its direction of travel after said reciprocable means has reversed its direction of travel. 90

9. A conveyer as claimed in claim 3, including means for reciprocating said carriage and said independently reciprocable means in a manner to cause the carriage to reverse its direction of travel after said reciprocable means has reversed its direction of travel. 95

10. In a conveyer adapted to move objects step by step lengthwise of a work support, the combination of laterally spaced means forming said support, a reciprocable carriage movable in one plane for a portion of its length of travel and in a higher plane for the remainder of said length, and relatively fixed laterally spaced means reciprocable as a unit independently of but supported by the carriage for moving the work lengthwise of said support when the carriage is moving in said higher plane. 100

11. In a conveyer adapted to move objects step by step along a work support, the combination of reciprocable means movable in one plane for a portion of its length of travel and in a higher plane for the remainder of said length, and object-supporting means mounted on and reciprocable longitudinally of said means for elevating and moving the objects relatively to said support when said means is moving in said higher plane. 110

12. In a conveyer as claimed in claim 1, said independently reciprocable means comprising a longitudinally extending frame work, and rollers interposed between said carriage and said frame work for supporting the latter. 115

13. In a conveyer as claimed in claim 3, said independently reciprocable means comprising a longitudinally extending frame work the under side of which is provided 125

with a track-way, and rollers mounted on said carriage and cooperating with said track-way for supporting said frame work.

14. In a conveyer as claimed in claim 3, said independently reciprocable means comprising a longitudinally extending framework and rollers interposed between said carriage and said frame work for supporting the latter.

In testimony whereof I affix my signature.

10 HORACE A. CARTWRIGHT.
